ATTORNEY.

UNITED STATES PATENT OFFICE.

NATHAN O. BOND, OF HYANNIS, MASSACHUSETTS.

EGG-BOILING DEVICE.

SPECIFICATION forming part of Letters Patent No. 623,200, dated April 18, 1899.

Application filed August 30, 1898. Serial No. 689,891. (No model.)

To all whom it may concern:

Be it known that I, NATHAN O. BOND, a citizen of the United States, residing at Hyannis, in the county of Barnstable and State of Massachusetts, have invented certain new and useful Improvements in Egg-Boiling Devices; and I do declare the following to be a full, clear, and exact description of the invention, such as will enable others skilled in the art to which it appertains to make and use the same, reference being had to the accompanying drawings, and to the letters of reference marked thereon, which form a part of this specification.

The object of my invention is to provide a simple and efficient device for boiling eggs which will automatically remove the eggs from the water at a predetermined time, thus preventing overcooking.

The invention consists in providing such a device with an automatic time mechanism by means of which the eggs are removed from the water after an interval regulated by the distance of travel of said mechanism and in the arrangement and construction and combination of parts with this end in view, as will be more fully described in the following specification, reference being had therewith to the accompanying drawings, in which—

Figure 1 is an elevation, partly in section, of my improved egg-boiler. Fig. 2 is a plan view of the same; Fig. 3, a detail of the time mechanism; and Fig. 4, a section on line xx of Fig. 3, looking in the direction indicated by the arrows in that figure.

Referring to the drawings, A is an upright tube provided at its lower end with legs aa , by means of which it may be supported upon the edges of a pan or boiler B. Within the tube A is fitted a plunger C, to the lower end of which is secured a pan D, provided with perforations dd in its bottom to permit the ingress and egress of water. The pan D and plunger C are normally held in an elevated position with relation to the boiler B by means of a spring E, attached at one end to the plunger and at its opposite end to the upper end of the tube A. A rod F is fitted to slide in a cap b at the upper end of the tube A and rest upon the plunger C, and a spring-catch c is secured to the lower end of the tube A and projects through an opening C' in the

side of the tube in such manner as to hold the plunger when it is depressed by pushing down upon the rod F.

Mounted upon the tube A in such manner as to slide thereon is a casing G, within which is mounted a clock-train H, the first gear K of this clock-train being adapted to mesh with a rack L on the outer side of the tube A and extending from the top of the same to a point about midway of its length. The casing G is formed of two parts $g'g'$, hinged to each other at their upper ends, as shown at g^2 , and held normally against each other by a spring g^3 , acting upon lugs g^4g^4 , mounted on each part of the casing. The part g' of the casing carries a small roller g^5 , mounted in such manner as to contact with the tube A at a point opposite the gear K and hold the same against the rack L.

The two parts of the casing are provided at their ends with thumb-pieces g^6g^6 , by means of which the train may be released from the rack and the casing moved freely up and down upon the tube A.

The action of the device is as follows: The eggs are placed in the pan D, and the pan pushed down by means of the rod F until it rests within the boiler B, in which position it is retained by the catch c . The casing G, which forms as a whole a weight to be dropped upon the catch to release the same, is raised any desired distance upon the tube A, and when released travels downward upon the same until the gear K reaches the end of the rack L, when it drops upon the catch c and releases it. The spring E within the tube A will then raise the plunger and pan D and remove the same from the boiler B.

It is obvious that the position of the clock-train upon the rack L will determine the time during which the pan and its contents will remain in the boiler.

The tube has formed upon the outside a scale of minutes and fractions, by means of which the time required for the descent of the casing and release of the catch may be determined.

It will be noted that there are few perforations in the bottom of the pan D. This construction is adopted in order that the weight of water contained in the pan may be utilized to prevent too rapid an ascent of the pan and

its contents and consequent breakage of the eggs.

Having thus described my invention, what I claim, and desire to secure by Letters Patent, is—

1. In an egg-boiler the combination of an upright tube provided at its lower end with spring-legs adapted to support the tube on a suitable boiler, a plunger moving within said tube, a pan connected to said plunger, a spring by which the pan and plunger are sustained in an elevated position, a rod for depressing the plunger, a catch for retaining the parts in a depressed position, and a weight sliding upon the upright tube and controlled by a time mechanism substantially as described.
2. In an egg-boiling device, the combination of an upright tube removably sustained upon a suitable boiler, a plunger moving within said tube, a pan sustained by said plunger, a spring by which the pan and plunger are sustained, a rod by which the pan and plunger may be depressed, a catch by which the parts are held in such position,

and a weight sliding upon the upright tube and controlled by a time mechanism by which the catch may be released as shown.

3. In an egg-boiling device the combination of an upright tube removably sustained upon a suitable boiler, a plunger moving within said tube, a perforated pan sustained by said plunger, a spring by which the pan and plunger are sustained, a rod by which said parts may be depressed, a catch by which said parts are held in a depressed position, a casing moving upon the vertical tube, a clock-train mounted within said casing, a rack carried by the vertical tube in position to mesh with the first gear of the clock-train and means for holding the gear and rack in mesh substantially as described.

In testimony whereof I affix my signature in presence of two witnesses.

NATHAN O. BOND.
